DESIGN FOR A CIGARETTE LIGHTER

Alfred F. Reilly, North Attleboro, Mass.

Application March 27, 1941, Serial No. 99,921

Term of patent 14 years

To whom it may concern:

Be it known that I, Alfred F. Reilly, a citizen of the United States, residing at North Attleboro, county of Bristol, and State of Massachusetts, have invented a new, original, and ornamental Design for a Cigarette Lighter, of which the following is a specification, reference being had to the accompanying drawing, forming a part thereof.

In the accompanying drawing,

Fig. 1 is a top plan view of a cigarette lighter showing my new design.

Fig. 2 is a front elevation of the same.

Fig. 3 is a left side elevation of the same.

Fig. 4 is a right side elevation of the same.

The dominant feature of my design resides in the top portion shown in full lines in the drawing.

I claim:

The ornamental design for a cigarette lighter, as shown and described.

ALFRED F. REILLY.
